J. Ned Williams INVENTOR
BY Charles L. Wright ATTORNEY

UNITED STATES PATENT OFFICE.

JOHN HOD WILLIAMS, OF WEST PALM BEACH, FLORIDA.

INLAY VULCANIZER AND PRESS.

Application filed September 1, 1923. Serial No. 660,460.

To all whom it may concern:

Be it known that I, JOHN HOD WILLIAMS, a citizen of the United States, and a resident of West Palm Beach, in the county of Palm Beach and State of Florida, have invented certain new and useful Improvements in Inlay Vulcanizers and Presses, of which the following is a specification.

This invention relates to improvements in 10 vulcanizers and particularly to types combined with a press, as used in connection with flasks containing molds formed of plaster, as in dental inlay and other work requiring a high degree of accuracy and refinement.

One of the objects of the invention is to provide a structure that can be used in vulcanizing rubber and analogous substances and also, without change, operate equally 20 well on firmer material, such as the pyroxylin group, including celluloid, etc., and also resinous groups such as phenolic condensation products, preferably in the form of round rods, whereby an extremely light, 25 strong plate may be obtained, tasteless, odorless, colored to suit and free from the objectional features of common plates made of metal and other material, in the ordinary manner.

Another purpose is to produce an apparatus in which the material in round rods is 30 pressed directly into the flask when closed and within the vulcanizer, the material being softened and rendered pliable within the 35 structure and forced directly into the mold under such pressure as may be required, all elements being component parts of the vulcanizer.

A further aim is in the provision of a 40 portable apparatus containing a steam generating chamber, heated by any convenient means and so arranged that the press elements may be removed and their chamber capped by a removable plug.

These several aims, objects and purposes, 45 together with others which will become apparent as the description progresses, are accomplished by the novel design, construction and combination of parts, hereinafter described and shown in the accompanying drawings, forming a material part of this disclosure and in which:—

Figure 1 is a longitudinal sectional view 50 taken through the center of an embodiment 55 of the invention,

Figure 2 is a top plan view of the same.

Figure 3 is a transverse sectional view taken on line 3—3 of Fig. 1, showing the top of the vulcanizer body.

Figure 4 is a bottom plan view of the removable upper portion of the vulcanizer, looking on line 4—4 of Fig. 1.

Figure 5 is a perspective view of the flask.

Figure 6 is a partial vertical sectional view, similar to Fig. 1, but showing a modification.

Figure 7 is a sectional view of the flask, illustrating the making of a mold therein.

Figure 8 is a similar view showing the cast as made.

Figure 9 is an enlarged fragmentary longitudinal sectional view taken through the upper part of the vulcanizer chamber, showing the press elements removed and a plug cap substituted.

Stated in general terms the invention consists of a cylindrical casing, raised by a tripod base from the surface on which it is operated to allow the use of any preferred heater, as a Bunsen burner for gas heater as shown.

Within the casing, above the burner, is a boiler having internal devices for supporting one or more flasks within the steam zone, above which is clamped a plate having a central conical extension provided with the elements of a screw press and carrying a steam relief valve, thermometer and like appurtenances.

Steam has access to the cone on top of the plate, surrounding a sleeve, removably held therein, which acts as a nut for the screw and also a pocket to receive the material, preferable in the form of a rod, and so arranged as to enter the opening in the center of the flask, when rendered sufficiently plastic by heat imparted from the steam and under pressure of the screw.

Referring more in detail to the drawings, the numeral 15 designates the cylindrical casing constituting the main body of the apparatus, in the lower end of which is secured a plate ring 16, formed with leg supports 17, having flanged feet 18 provided with openings 19 to receive fastening means by which the apparatus may be secured on a bench or like foundation.

Any preferred number of legs may be used and their length is such as to readily admit of a heater, as the Bunsen burner 20, to be placed below the casing, the burner tube 21 extending above the ring as shown,

gas being connected to the burner by the tube 22 and controlled by the cock 23.

An opening 24 in the casing provides means for igniting the gas in the burner 5 end, the flame impinging upon the convex bottom of a boiler, generally designated by the numeral 25, this boiler having at its top an annular flange 26 extending outward and resting on a ring 27 seated on top of 10 the casing 15 and having a reduced portion fitted to enter the casing and be secured therein.

The main circular portion of the boiler 25 has on one side a heavy, inwardly extending rib 28 and is formed with other 15 equally spaced vertical ribs 29 adapted to enter openings in grates 30 and 31, respectively lower and upper, the lower grate resting in the boiler near its curved bottom, 20 above the normal level of the water.

These grates are interchangeable and in 25 case two flasks are used, as in ordinary vulcanizers, one grate only is used, but if the apparatus is used as a press for firmer material, the lower grate is provided with supports 32 upon which the upper grate rests, guided by the ribs as shown.

The flask is preferably composed of a cup-like base element 33, above which is a ring 30 34, surmounted by a cap or cover 35, the latter having a convex upper wall containing a central cavity 36 from which leads a central vertical opening 37 to the interior of the flask.

35 Other, smaller, lateral openings 38 are formed at the junction of the ring and base, partially in each, so that an excess of material may escape.

The general shape of the flask is circular, 40 flattened at one side, and formed to engage the ribs in the boiler, and the sections are interlocked in such manner as to prevent relative displacement, the mold being formed in the usual manner.

45 Seated on the flange 26, which is provided with a depressed groove 39 for a packing ring, is a plate 40 having lateral extensions 41 containing notches 42 to receive bolts 43 pivoted on pins 44 passing through 50 ears 45 integral with the ring 27 and provided with nuts 46 by which the plate 40 may be firmly clamped to the boiler flange.

Extending centrally upward from the plate 40 is a generally conical projection 47 55 containing a chamber 48 and having in its lower portion an integral block 49, there being steam passages 50 through it, in communication with the boiler which the plate covers.

60 This block is internally screw-threaded to receive the lower end 51 of a sleeve 52, the lower extremity of which is convex to suit the cavity 36 of the flask cap.

The larger diametered, main portion of 65 the sleeve passes through a packing ring 53

set in a seat in the upper part of the cone 47 and is compressed by a hollow packing screw 54, threaded into the top of the cone and through which the sleeve passes.

At the upper end of the sleeve is a head 70 55 suited to receive a wrench and extending from the head is a threaded thimble 56 having engaged with it a combined lock and packing nut 57.

The lower end 51 of the sleeve is smooth 75 bored to receive a short length of the material M to be molded, preferably in rod form, and adapted to be pressed downward by a plunger 58 rotatably attached to the end 59 of the press screw 60, this screw 80 being threaded into the main portion of the sleeve 52 and carrying the lock nut 57, above which it extends, and is provided with a square head 61 to receive a wrench.

In the modification shown in Fig. 6, a 85 spring 62 is interposed between the plunger 58 and end of the screw, this form being used when a compressible plastic is being molded.

Fig. 9 shows the apparatus with the sleeve 90 52 and screw 60 removed, and in place of the sleeve a solid plug 63 is inserted in the top of the cone.

In all cases the plate 40 is drilled and tapped, at 64, to receive a casing 65 for the 95 thermometer 66, and it is to be noted that the thermometer is in direct communication with the interior of the boiler and thus subject to its variations of temperature.

Screw threaded into the cone 47 is a steam 100 relief valve 67 provided with a handle 68 convenient for operation and which may be used for blowing off the boiler when desired.

Figs. 7 and 8, showing sections of the 105 flask, illustrate the manner of forming the molds, the plaster being represented by P, the teeth, T, and the plate, as cast, is shown therein.

The operation is very simple, first forming 110 the mold within the flask in the usual manner, entering water into the boiler, filling a proper quantity of material into the sleeve and clamping the cone carrying cover over the boiler.

Upon application of heat, steam is raised, 115 circulating about the flask and entering the cone, causing the material to become softened, whereupon pressure is applied by the screw, forcing the material into the flask 120 in a plastic condition, causing it to flow to every part of the mold, any excess appearing at the small openings 38.

When the cast is completed, the upper portion of the apparatus is unbolted and the 125 flask removed to be treated in the usual manner.

Although I have described my improvements with considerable detail and with respect to certain particular forms of my in- 130

vention, I do not desire to be limited to such details since many changes and modifications may well be made without departing from the spirit and scope of my invention in its 5 broadest aspect.

Having thus described my invention, what I claim as new and desire to secure by Letters Patent, is:—

1. A vulcanizer press containing a boiler 10 body, a flask removably engaged therein, a chambered cover clamped over said body, a sleeve adjustable in said cover to extend outward thereabove, said sleeve registering with and clamping said flask, a plunger 15 movable in the sleeve, a screw operative in said sleeve adapted to press said plunger against material contained therein directly into said flask and a spring interposed between the screw and plunger.

2. A vulcanizer comprising an upright 20 cylindrical casing, a boiler supported within said casing, a heating means, grates removably disposed in said boiler, means for spacing said grates, in vertical relation, ribs extending in from the wall of said boiler for 25 positioning the grates, and a cover over said boiler removably clamped to said casing.

3. A vulcanizer comprising an upright 30 cylindrical casing, a stand on which said casing is supported, a boiler suspended within said casing, means extending through said stand for heating said boiler, said boiler having internal longitudinal ribs, one of said 35 ribs extending inward to a greater extent than the others, grates disposed in said boiler, said grates being guided by said ribs, a flask supported on one of said grates, said flask engaging said ribs, a chambered cover gasketed to the top of said boiler, and means 40 carried by said casing for clamping said cover thereover.

4. A vulcanizer comprising an upright 45 cylindrical casing, a stand on which said casing is supported, a boiler fixed in said casing said boiler having internal vertical ribs, means for heating said boiler, said casing having an opening for igniting the heating means, a flask suited to enter said boiler, supports for said flask engageable with said 50 ribs, a domed cover having means for sealing said boiler, clamping means for said cover carried by said casing a sleeve adjustable in said cover and adapted to contact with the flask, the opening in said flask registering with the bore of said sleeve, and means including a spring pressed plunger 55 for forcing material from said sleeve into the flask.

5. A combined vulcanizer and press comprising a casing, a boiler therein, means for heating said boiler, a flask supported in said boiler, a cover removably secured over said boiler, said cover having a raised steam 60 chamber, a sleeve adjustably and removably

engaged in said chamber, the end of said 65 sleeve entering a cavity in the top of said flask, a packing nut for said sleeve at the top of said chamber, and a plug interchangeable with said packing nut.

6. A combined vulcanizer and press comprising a casing, a boiler therein, means for heating said boiler, a flask supported in said boiler, a cover removably secured over said boiler, said cover having a central raised 70 hollow extension constituting a steam chamber and a partial web level with the lower surface of the cover, a sleeve screw threaded into said web, a packing nut in the top of said chamber through which said sleeve extends, a screw operable in said sleeve, a plunger actuated by said screw within the lower part of said sleeve, said sleeve impinging on the top of said flask and carrying material to be entered therein, and means for locking said screw to said sleeve. 75

7. A vulcanizer press containing a steam chamber having internal longitudinal ribs, a flask removably engaged therein, said flask having a cylindrical opening in its cover a concave recess circumjacent thereto, and projections on its sides engageable with said ribs, an adjustable sleeve having its lower end fitted to engage the recess in the flask cover, said sleeve being adapted to contain a cylindrical rod of the material to be molded, and means for pressing the rod when softened into said flask. 80

8. A vulcanizer press containing a ribbed steam chamber, a flask removably engaged therein, said flask having a cylindrical opening in its cover and a concave recess circumjacent thereto, means on said flask cooperative with the ribs in said chamber adapted to prevent relative rotation, an adjustable sleeve engaging the flask cover, said sleeve having a bore exceeding the diameter of the hole in said flask, the bore of the sleeve being adapted to contain a cylindrical rod of material, and means for forcing the rod when in pliable condition into said flask. 85

9. A vulcanizer press containing a steam chamber, a flask removably engaged therein, said flask having a flattened side, a cylindrical opening in its cover, and spaced openings between the lower and intermediate sections on one side thereof means for maintaining a rod of material to be molded above and in register with the opening in the cover of said mold where it will be subjected to heat from said steam chamber, means for forcing the rod when rendered plastic into said mold, the excess material passing out of the side openings in the flask and means cooperating between said chamber and flask to prevent relative rotary motion. 90

In testimony whereof I have signed my name to this application.

JOHN HOD WILLIAMS
